[57] CLAIM

The ornamental design for a VCR, as shown and described.

DESCRIPTION

FIG. 1 is a top, front and right side perspective view of a VCR showing our new design;

FIG. 2 is a left side elevational view thereof, rotated 90 degrees from FIG. 3;

FIG. 3 is a top plan view thereof;

FIG. 4 is a right side elevational view thereof, rotated 90 degrees from FIG. 3;

FIG. 5 is a front elevational view thereof;

FIG. 6 is a rear elevational view thereof; and

FIG. 7 is a bottom plan view thereof.

Fig. 1
